Inventor

UNITED STATES PATENT OFFICE.

JOHN A. SCHMITT, OF COLUMBUS, OHIO, ASSIGNOR TO THE UNIVERSAL MILKING MACHINE COMPANY, OF COLUMBUS, OHIO, A CORPORATION OF OHIO.

PULSATATOR FOR MILKING MACHINES.

Application filed November 28, 1922. Serial No. 603,727.

To all whom it may concern:

Be it known that I, JOHN A. SCHMITT, a citizen of the United States, residing at Columbus, in the county of Franklin and State of Ohio, have invented certain new and useful Improvements in Pulsators for Milking Machines, of which the following is a specification.

My invention relates to fluid pressure actuated pulsators or alternators for milking apparatus and analogous purposes.

The present application is a continuation and further development of the subject matter of my co-pending applications for Letters Patent Serial No. 505,257, filed October 4, 1921, and 539,167, filed February 25, 1922.

While involving the same general structural features and mode of operation, the present invention contemplates an improved form of tumbler mechanism for intermittently reversing the fluid pressure control valve and an improved and more economical means for connecting the actuating piston with the movable parts. Whereas the previous constructions referred to involved the use of a tension spring shifted to and fro past a dead center relation, with the valve to be operated, upon which it exerts a constant pulling influence, first in one direction and then in the other, the present construction is dependent upon a push and pull mode of transmitting movement from the prime actuator to the movable valve, the movement of the valve being effected wholly upon one side of a dead center position, the valve being actuated by the reaction of a compression spring, intermittently compressed by both the push and pull impulses of the power transmission devices. This is accomplished by means of a telescopic power transmission link having the compression spring so interposed between the relatively movable telescopic members of the link, that both the extension and contraction of such telescopic link will place the spring under compression. This telescopic link is connected eccentrically with a pivoted fluid pressure control valve, which is thereby moved to and fro across the path of travel of a continuously moving alternating stop member, with which the valve structure engages, first upon one side and then upon the other to hold the valve against operative movement until the stop member

and connected parts approach the limit of their stroke in either direction. The connection between the actuating piston and the initial member of the valve tumbling mechanism is effected by a feather or key, carried by or movable with the piston stem and having sliding engagement in a key way or slot in the main structure or mounting and a non-sliding engagement in an elongated slot in the operated member, whereby the latter is maintained in proper alignment during its reciprocation in unison with the piston.

The object of the invention is to simplify the structure as well as the means and mode of operation of valve reversing or tumbling mechanism for pulsator structures and the like, whereby they will not only be cheapened in construction, but will be more efficient in use, positive in operation, uniform in action, of increased durability, and unlikely to get out of repair.

A further object of the invention is to afford a structure possessing definition to its snap over movement or reversal at the limit of the operative stroke, and to further afford a construction employing a compression spring, which will afford greater uniformity of action and longer period of usefulness, than a spring subjected to elongation.

A further object of the invention is to afford a structure which may be produced with inexpensive machine operation, and which will require minimum adjustment and accuracy of fit, the valve members being of a substantially free floating type, subjected to minimum displacement strain, whereby they will tend to automatically find their seat, and maintain close contact under preponderance of atmospheric pressure.

A further object of the invention is to provide an improved connection between the prime actuator and the operated member, which will maintain the latter in predetermined aligned path of travel without presenting difficulties or obstructions to economical machine operations.

A further object of the invention is to provide an improved safety device for the throttle control member, which while permitting ready and easy adjustment, will prevent accidental change of adjustment under influence of vibration.

With the above primary and other incidental objects in view as will more fully appear in the specification, the invention consists of the features of construction, the parts and combinations thereof, and the mode of operation, or their equivalents as hereinafter described and set forth in the claims.

In the accompanying drawings, wherein is shown the preferred, but obviously not necessarily the only form of embodiment of invention, Fig. 1 is a top plan view of the assembled pulsator showing the parts of the tumbler mechanism approaching the limit of their stroke in the direction indicated by the darts. Fig. 2 is a side elevation of the assembled pulsator structure. Fig. 3 is a top plan view similar to Fig. 1, but showing the operating parts approaching the opposite limit of their stroke in the direction indicated by the darts. Fig. 4 is a top plan view of the main structure or mounting with the valve tumbling mechanism removed. Fig. 5 is a vertical sectional view. Fig. 6 is a detail sectional view through the reversible control valve and its carrier. Fig. 7 is a detail perspective view of the control valve and its actuating parts disassembled. Fig. 8 is a detail perspective view of the telescopic power transmission link with the compression spring removed. Fig. 9 is a perspective view showing the under side of the oscillatory control or locking member for the control valve. Fig. 10 is a perspective view showing the under side of the reciprocating pulsator valve. Fig. 11 is a perspective view of the connecting key for transmitting movement from the piston stem to the reciprocating pulsator valve. Fig. 12 illustrates a modification.

Like parts are indicated by similar characters of reference throughout the several views.

The structure herein shown is particularly adapted for being mounted upon the lid or cover of a pail or receiver, which will form the closure for the bottom of the vacuum chamber contained in the base of the structure. Otherwise the pulsator is mounted upon a suitable base, not shown, in lieu of such pail or receiver lid. In the particular form of embodiment illustrated, the pulsator comprises a vertically disposed cylindrical chambered base 4, carrying at one side thereof a laterally disposed integral short cylinder portion 5, and adjacent to this cylinder 5 and forming the top of the base 4 or vacuum chamber is a flat table like valve bearing surface 6. Upon this bearing surface or valve table 6, the pulsator and control valve are preferably mounted. The vacuum chamber 7 within the base 4 is provided with a nipple or spud 8, through which it communicates with any source of suction such as a vacuum tank, a pump or

other such device. The head of the base 4 immediately beneath the valve bearing surface is provided with a transverse bore 9, communicating with the interior of the cylinder 5, and within which bore reciprocates a piston stem 10, connected within the cylinder 5 to a piston head. The piston head is actuated to and fro by alternation of atmospheric pressure on opposite sides thereof. It comprises two oppositely disposed tapered discs 11, between which is disposed an annular collar or ring 12 of packing material, such as leather, rubber composition or other suitable substance. By relative adjustment of the tapered disc 11, by means of a clamp nut 13, upon the extremity of the piston rod, the annular packing 12 may be subjected to greater or less compression and so expanded into engagement with the walls of the cylinder 5.

The piston is actuated to and fro by alternately connecting the opposite sides of the piston with atmosphere and with the suction or vacuum chamber 7 respectively. To this end, the valve table 6 is provided with a group of three ports 17, 18 and 19. The intermediate port 17 extends downwardly through the head or top of the pulsator body and communicates at its lower end with the vacuum chamber 7, which in turn is directly connected by a nipple or spud 8, with a source of suction. The port 18 communicates through a lateral passage 18', shown by dotted lines, with the inner end of the cylinder 5. The remaining port 19 is likewise connected through a communicating passage 19' with the outer end of the cylinder 5 and beyond the piston head. These ports are controlled by an oscillatory control valve 20, pivotally mounted upon a stud 21, and oscillated to and fro to alternately connect the suction port 17 with the respective ports 18 and 19. The disconnected port being uncovered by the movement of the valve 20 admits air at atmospheric pressure to the cylinder. At the same time, the opposite end of the cylinder is connected through the corresponding passage and port with the vacuum chamber 7. As a result the atmospheric pressure upon the piston head will shift the piston toward the end of the cylinder connected with the suction or vacuum chamber. This movement of the piston is transmitted to the valve 20 to reverse the position of the valve and the communication of the ports controlled thereby to admit air pressure to the opposite side of the piston 10 and reversing the connection of the cylinder 5 with the suction or vacuum chamber 7. Adjacent to the opposite side of the valve table 6 is a second group of ports 23, 24 and 25, constituting the pulsator ports and controlled by the reciprocating pulsator valve 26. The intermediate port 23 communicates with the vacuum chamber 130

7, while the ports 25 and 26 are independently connected with a separate teat cup connection in this instance a Y connection 27. The teat cup clusters are connected with the connections 27, and alternately actuated as the valve 26 is reciprocated.

The pulsator valve 26 is recessed on its under side at 26' to afford an intercommunicating passage between the intermediate 10 port 23 and the respective ports 24 and 25, when the valve is at the opposite limits of its stroke. At one limit of its movement the valve 26 connects the ports 23 and 24, leaving the port 25 open to atmosphere, while at 15 its opposite stroke this connection is reversed, opening the port 24 to atmosphere and connecting the port 25 with the source of suction through the port 23.

As thus far described the structural features are quite similar to the prior constructions referred to.

The reciprocating pulsation valve 26 is slotted or splined on its under side as at 28 for engagement over a key or feather 29, 25 carried by the rear end of the piston stem 10 and projecting above the top surface of the valve table 6. This connecting key may be of any suitable form. However, in the drawing, it has been shown of a substantially 30 T shape, having a laterally disposed screw stem 30, engaging in a screw threaded hole, in the extremity of the piston stem 10. There is formed in the table surface 6, a slot 33, communicating with the bore 9. The 35 piston stem 10 extends within the bore 9 while the T shaped key or coupling member 29 is inserted through the slot 33, and is engaged therewith by rotating the piston and stem by means of the slotted outer extremity 40 31 of the piston stem, to interengage the stem 10 and key or coupler 29. The head or engaging portion of the key or coupler 29 being alined with the threaded stem 30 and with the piston stem 10 maintains the alignment 45 of the reciprocating pulsator valve 26 during its reciprocating movement. The pulsator valve 26 thus rests loosely upon the bearing or table surface 6 and is pressed thereon by atmospheric pressure, the under 50 side of the valve particularly the recess 26' being subjected to suction or vacuum. Thus atmosphere forms a preponderance of pressure upon the top of the valve holding it to its bearing upon the surface of the table 6. 55 The same is true of the control valve 20, which likewise is subjected to suction or vacuum on its under side, through the port 17 while atmosphere affords a preponderance of pressure upon the top. The bearing 60 surfaces for the valve particularly the pulsator valve 26 is slightly raised above the general surface of the table 6 as particularly shown in Fig. 4, and the valve as it travels to and fro extends slightly beyond the limit 65 of such bearing surface in either direction.

This slight elevation of the bearing surface materially facilitates the manufacture and finishing of such surfaces and the tension of the valve laterally beyond the limit of such bearing surface and its movement 70 slightly beyond the extremity of the bearing surface at the limit of its stroke makes the valve self cleaning. That is to say any sediment, dust or accumulation of oil upon the bearing surface will be pushed by the valve 75 off such surface onto the surrounding clearance space. The clearance of this bearing surface may be very slight.

The pulsator valve 26 being connected with the piston stem 10 through the key or 80 coupler 29, reciprocates in unison with the piston and alternates the connection of the teat cup spuds 27, with the suction or vacuum chamber 7. This movement of the pulsator valve alternately subjects each of the 85 teat cup spuds 27 to the admission of air at atmospheric pressure and to exhaustion through connection with the vacuum chamber 7.

This to and fro movement of the pulsator valve is transmitted to the control valve 20 to effect its alternation as the piston and with it the pulsator valve 26 approach the limit of their movement in either direction. The alternation of the control valve 20 in 90 turn admits actuating fluid, i. e. air at atmospheric pressure alternately to opposite sides of the piston head. In the present instance, the construction is such that the control valve 20 is automatically locked in its 95 operated position until the pulsator valve and piston approach the opposite limits of their stroke, whereupon the control valve is not only unlocked, but is actuated with a snap over movement to its reverse position. 100

The fluid pressure control valve 20 is actuated to and fro by means of a valve carrier 35, pivoted concentrically with the valve 20 upon the stud 21. The valve and carrier are interengaged to oscillate in unison yet leaving the valve 20 free for independent adjustment toward its valve seat under atmospheric pressure and relieving the valve itself from incidental unseating pressures or strains. This valve 20 is provided in its 110 under face with an elongated recess or port 36 of sufficient extent to connect the port 17 with either the ports 18 or 19, according to the position of the valve. For economy of manufacture, this valve 20 may be stamped 115 from sheet metal. The stamping operation in forming the port or recess 36 embosses or raises upon the top of the valve a corresponding rib or bead 37, which for economy 120 is utilized to operatively interengage the valve with the carrier 35. This carrier 35 is provided with an arcuate slot 38, in which the projecting rib or bead 37 of the valve 20 engages.

The carrier 35 is actuated to and fro by 130

alternating push and pull impulses, transmitted from an oscillatory control member 40, pivoted to the main structure at 41, and overlying the reciprocating pulsator valve 26. The control member 40 carries on its under surface a stud or lug 42, which engages in a notch 42', in the top surface of the pulsator valve 26, thereby causing the control member 40 to move in unison with the pulsator valve and the piston alternately in opposite directions. The oscillatory control member 40 carries upon its upper surface a projecting stud 43, operatively connected by a telescopic link, with a stud 44, eccentrically positioned upon the oscillatory valve carrier 35. The telescopic power transmission link comprises two slotted members, relatively movable in longitudinal direction and arranged in overlapping relation. One of these members 45 has slotted engagement with the stud 43, of the control member 40, while the other slotted member 45 of the telescopic link has slotted sliding engagement with the eccentric stud 44 of the valve carrier. The overlapping ends of the slotted member 45 are provided with **T** heads or offset shoulders 46, which afford abutments for the opposite ends of the compression spring 47, which surrounds and encloses the overlapping portions of the link members 45, intermediate the heads or shoulders 46. The construction is such that whether the pull is outwardly upon the extreme ends of the overlapping slotted members or the push inwardly upon the mean or overlapped ends of the slotted members, the effect upon the spring 47 is the same, causing the spring to be compressed in order that by its reaction it may transmit a like impulse, that is push or pull upon the valve carrier to reverse the valve. In other words, the pulling effort or pushing effort as the case may be of the oscillating control members 40 is stored in the spring 47, by subjecting the spring to compression, to be later transmitted to the valve carrier. The valve carrier is provided with an upwardly projecting stop pin 48 at its free end, while the oscillatory control member 40 is provided with a coacting dependent flange or lip 49. Under the pushing impulse of the control member, whereby the valve carrier tends to turn inwardly as shown in Fig. 1, the stop pin 48 rides upon the exterior margin of the flange 49 until the control member reaches the limit of its stroke, whereupon the pin will pass the end of the flange as the valve reverses under the influence of the spring expansion. During the return movement under the pulling influence of the control member, the stop pin 48 will ride upon the inner face of the flange or lip 49 until the control member reaches the opposite limit of its stroke, whereupon the valve 65 will again be reversed by a second expansive

movement of the spring. The stop pin 48 of the valve carrier thus moves to and fro across the path of travel of the dependent flange or lip 49 of the control member, engaging the flange first upon one side and then upon the other. The movement of the valve is limited by such engagement until the parts approach the limit of their stroke in either direction, whereupon the valve is released for reversal under the expansion of the spring. During the movement of the parts in one direction as shown in Fig. 1, wherein the control member exerts a pushing impulse, the studs 43 engage the head of the opposite slotted link member 45 carried by the valve carrier stud, while the stud 44 of the valve carrier forms an abutment for the head of the slotted link member, carried by the control member stud 43. The movement of the stud 43 toward the valve carrier stud 44 forces the head 46 of the respective link members toward each other, placing the spring 47 under compression. As the stop flange 49 of the control member passes beyond the pin 48, the expansion of the spring oscillates the valve carrier from the position shown in Fig. 1 to that shown in Fig. 3. During the return stroke whereby the control member exerts a pulling impulse, the studs 43 and 44 engage in the extreme ends of the slots of the respective members 45, tending to reciprocate the members 45 outwardly in opposite directions, thereby again causing the heads 46 of the link members 45 to move toward each other and again placing the spring 47 under compression. At the opposite limit of the stroke, the stop flange 49 again passes beyond the pin 48, but in the opposite direction, thereby releasing the valve carrier, which by the expansion of the spring is returned to the position shown in Fig. 1. It will be observed that the oscillation of the control valve carrier 35, occurs wholly upon one side of a head center position. That is to say, the valve does not reverse to and fro across a dead center position, neither is the actuating spring carried to and fro across a dead center point to exert its influence in different directions, as is a very common expedient. Likewise it is to be noted that although the valve is actuated by alternating push and pull impulses, the actuating spring 47 is compressed by both impulses and by its subsequent expansion exerts its influence first in one direction, and then in the other, to transmit the initial push or pull impulse, to the oscillatory valve.

The speed with which the alternation or reversal occurs is controlled by regulating the capacity of the control port 17. To this end there is provided an adjusting screw 50, which intersects the port passage and by its adjustment serves to reduce the capacity of the port and hence the volume of air passing therethrough and so retard the speed of 130

operation. It has been customary to provide such throttle screws with lock nuts, by which they may be maintained in adjusted relation. However, the use of a lock nut has been found troublesome in that the lock nut frequently sticks or jams, necessitating the use of tools to release it. To overcome this difficulty a spring 51 is provided, which surrounds and encloses the exposed portion 10 of the throttle screw, abutting at one end upon the head of the screw and at its opposite end upon the main supporting structure. This spring is compressed as the screw is adjusted inwardly. The frictional engagement of the spring with the screw head and with the frame of the device under its 15 expensive influence is sufficient to maintain the throttle screw in adjusted position, permitting free and ready adjustment of the screw by the fingers of the operator. The entire tumbler mechanism may be enclosed within a suitable cap or housing to be mounted upon the top of the structure shown. However, inasmuch as such cap 20 does not in any way affect the function or operation of the parts to avoid complication, it has been omitted.

The detail view Fig. 12 has been shown as a modification, wherein the oscillatory 30 control member 40 has been wholly omitted, and the stop flange 49', corresponding to the flange 49 before described is mounted directly upon the reciprocatory pulsator valve 26. This dependent flange 49' performs the same locking function, in controlling the valve carrier 35 as before described. In lieu of the actuating stud 43 carried by the control member, a corresponding stud 43' is mounted directly upon 35 the reciprocatory valve 26 and connected with the telescopic links, thus transmitting movement directly from the reciprocatory valve 26 to the control valve carrier 35.

From the above description it will be apparent that there is thus provided a device 45 of the character described possessing the particular features of advantage before enumerated as desirable, but which obviously is susceptible of modification in its 50 form, proportions, detail construction and arrangement of parts without departing from the principle involved or sacrificing any of its advantages.

While in order to comply with the statute 55 the invention has been described in language more or less specific as to structural features, it is to be understood that the invention is not limited to the specific details shown, but that the means and construction 60 herein disclosed comprises the preferred form of several modes of putting the invention into effect and the invention is therefore claimed in any of its forms or modifications within the legitimate and valid 65 scope of the appended claims.

Having thus described my invention, I claim:

1. In a pulsator mechanism of the character described, wherein a fluid pressure actuated mechanism operates to alternately 70 subject a pair of pulsation conduits to variations of fluid pressure characterized by an alternating member actuated by said pressure operated mechanism, an oscillatory control valve for the fluid under pressure 75 and an extensible and contractile link between the alternating member and the oscillatory valve transmitting alternate push and pull movements from the alternating member to the oscillatory valve. 80

2. In a pulsator mechanism of the character described, wherein a fluid pressure actuated mechanism operates to alternately 85 subject a pair of pulsation conduits to variations of fluid pressure characterized by an alternating member, actuated by said pressure operated mechanism, an oscillatory control valve for the fluid under pressure, and a compression spring compressed by the movement of the alternating member in 90 each direction which by its successive reactions actuates the control valve in alternate directions without passing a dead center position in relation with the valve.

3. In a pulsator mechanism of the character described, wherein a fluid pressure actuated mechanism operates to alternately 95 subject a pair of pulsation conduits to variations of fluid pressure, characterized by an alternating member actuated by said pressure operated mechanism, an oscillatory control valve for the fluid under pressure, a link connecting the alternating member and the valve comprising two overlapping longitudinally adjustable sections having sliding 100 engagement with both the alternating member and the valve and also with each other, and a spring common to the overlapping portions of both sections, tensioned by the relative adjustment of the sections under influence of the alternation of the alternating member, the reaction of which spring acting through the engaged link section reverses the valve. 105

4. In a pulsator mechanism of the character described, wherein a fluid pressure actuated mechanism operates to alternately subject a pair of pulsation conduits to variations of fluid pressure characterized by an 115 alternating member actuated by said pressure operated mechanism, an oscillatory control valve for the fluid under pressure, a telescopic link interposed between the alternating member and the oscillatory valve and telescopically adjusted by the movement of 120 the reciprocating member, and a spring tensioned by both elongation and contraction of the telescopic link, the reaction of which reverses the valve in alternate directions. 125

5. In a pulsator mechanism of the character 130

- ter described, wherein a fluid pressure actuated mechanism operates to alternately subject a pair of pulsation conduits to variations of fluid pressure characterized by an 5 alternating member actuated by said pressure operated mechanism, an oscillatory control valve for the fluid under pressure, a link comprising two overlapping relatively movable sections, each section having a stop portion at its overlapped end, a slot in each section, extending beyond the overlapped portions, studs carried by the alternating member and the valve member engaging through said slots which when moved one 10 away from the other engage the ends of the slots to extend the overlapping link sections and when moved one toward the other engage the overlapping ends to likewise extend the sections, and a compression spring 15 mounted intermediate the stop portions of the overlapping ends of the sections, and compressed by the relative movement of said sections in either direction which by its reaction will reverse the control valve.
- 20 6. A motion transmitting link comprising two overlapping slotted members having stop means at their overlapping ends, and a compression spring interposed between the stop means of the respective members, and 25 relatively movable studs engaging in the slots of the respective members adapted by their relative adjustment to or from each other to extend said link against the tension of the spring.
- 30 7. A pulsator apparatus wherein a pulsator conduit is intermittently subjected to fluctuations of fluid pressure by operation of a fluid pressure actuated operating mechanism, characterized by an oscillatory valve 35 to be intermittently actuated controlling the action of the fluid under pressure an oscillatory control member having continuous alternating movement, the valve and control member being movable in intersecting paths 40 of travel wholly at one side of a dead center position, the movement of the valve being limited first in one direction and then in the other by the position of the control member until said control member approaches the 45 limit of its stroke in either direction, and a spring tensioned by the movement of the control member in either direction which by its reaction shifts the valve upon the movement of the control member out of the 50 path of travel of the valve.
- 55 8. A pulsator apparatus wherein a pulsator conduit is intermittently subjected to fluctuations of fluid pressure by operation of a fluid pressure actuated operating mechanism characterized by an oscillatory valve 60 to be intermittently actuated controlling the action of the fluid under pressure, an oscillatory control member having continuous alternating movement, the valve and control member being movable in intersecting paths

of travel wholly at one side of a dead center position, the movement of the valve being limited first in one direction and then in the other by the position of the control member until said control member approaches the 70 limit of its stroke in either direction, and a compression spring compressed by the movement of the control member in either direction, the reaction of which will shift the valve when the control member moves out of 75 the path of travel of said valve.

9. A pulsator apparatus wherein a pulsator conduit is intermittently subjected to fluctuations of fluid pressure by operation of a fluid pressure actuated operating mechanism characterized by an intermittently operated oscillatory valve controlling the action of the fluid pressure and a continuously alternating oscillatory control member, moving in intersecting paths of travel 80 wholly at one side of a dead center position, a stop flange upon the control member and a stop upon the valve engaging the stop flange of the control member first on one side and then upon the opposite side and released to permit movement of the valve only as the control member approaches the limit of its stroke in either direction, and a spring tensioned by the movement of the control member to shift the valve when so released. 90

10. A pulsator apparatus wherein a pulsator conduit is intermittently subjected to fluctuations of fluid pressure by operation of a fluid pressure actuated operating mechanism characterized by an intermittently operated oscillatory valve controlling the action of the fluid pressure and a continuously alternating oscillatory control member, moving in intersecting paths of travel 100 wholly at one side of a dead center position, said control member limiting the movement of the valve until the control member approaches the limit of its stroke, and an actuating link connecting the control member and valve transmitting alternating push and 105 pull impulses through the link to said valve, by which the valve is reversed at predetermined points in the cycle of operation.

11. In a pulsator mechanism wherein a pulsator conduit is subjected to intermittent fluctuations of fluid pressure by operation of a fluid pressure actuated operating mechanism, characterized by an oscillatory valve controlling the action of the fluid pressure, a reciprocatory pulsator valve, an oscillatory control member operatively engaged with the reciprocatory pulsator valve for oscillatory movement in unison therewith, an alternating push and pull link connecting the control member and said fluid pressure control valve, which shifts the valve upon the approach of the pulsator valve to either limit of its stroke. 115

12. In a pulsator apparatus, wherein a pulsator conduit is intermittently subjected 120

- to fluctuations of fluid pressure by operation of a fluid pressure actuated mechanism including a reciprocatory piston and a pulsator valve movable in unison with the piston, 5 characterized by a spline carried by the piston and engaging in the under side of the pulsator valve to connect said parts in predetermined alined relation for unison movement.
- 10 13. In a pulsator apparatus wherein a pulsator conduit is intermittently subjected to fluctuations of fluid pressure by operation of a fluid pressure actuated mechanism including a reciprocatory piston and a pulsator valve movable in unison with the piston, 15 characterized by a substantially T-shaped connector carried by the piston and engaging with the pulsator valve to maintain the valve in predetermined relative relation during the unison reciprocation of the piston and valve.
14. In a pulsator apparatus wherein a pulsator conduit is intermittently subjected to fluctuations of fluid pressure by operation 20 of a fluid pressure actuated mechanism including a reciprocatory piston and a pulsator valve movable in unison with the piston, 25 characterized by a connector engaged in the end of the piston stem and having a

sator valve movable in unison with the piston, characterized by a stud having a polygonal head engaging in a corresponding recess in the pulsator valve to maintain the 30 valve in predetermined relative relation during the reciprocatory movement thereof.

15. In a pulsator apparatus wherein a pulsator conduit is intermittently subjected to fluctuations of fluid pressure by operation of a fluid pressure actuated mechanism including a reciprocatory piston and a pulsator valve movable in unison with the piston, 35 characterized by a connector engaged in the end of the piston stem and having a standing portion surmounted by an elongated head engaging in a corresponding recess in the valve to operatively connect the valve and piston for unison movement.

In testimony whereof, I have hereunto 40 set my hand this 10th day of September A. D. 1922.

JOHN A. SCHMITT.
